MULTIROLL CHOCOLATE REFINER AND
LIKE MACHINESAllan Ashmead Tunley, Peterborough, England,
assignor to Baker Perkins Limited, Peter-
borough, EnglandApplication May 26, 1950, Serial No. 164,419
In Great Britain May 30, 1949

3 Claims. (Cl. 241—32)

1

This invention relates to multi-roll chocolate refining machines, such as five-roll refiners, or similar machines in which a feed roll is provided for supplying the material to be treated to the lowest or first of the refining rolls.

In such machines there is a danger of some hard or resistant foreign body being accidentally fed, together with the supply of the material to be ground or treated, into the nip between the feed roll and the first refiner roll. Should this occur damage to the machine is liable to arise if separation at the nip to allow the obstruction to pass does not take place.

In order to permit this separation, shear pins have been employed in mechanism which holds the feed roll up to its work, for example, a shear pin has been introduced in the hand wheel mechanism provided at each end of the feed roll for adjusting the nip thereof in relation to the first refiner roll. By this arrangement any obstruction liable to produce undue strain in its passage through the nip is intended to cause shear pin rupture to take place and the feed nip to be relieved.

This arrangement is not altogether satisfactory as the complete relief of the nip is dependent upon both pins being sheared, which is likely only to occur if the obstruction resides precisely in the middle of the length of the roll. The fracture of a single pin in the arrangement exemplified above is also unsatisfactory as it affords relief at one end only of the feed roll, causing such to tilt, and this tilting may not be sufficient to clear the obstruction and it may also damage the roll gears.

Accordingly the aim of the present invention is to overcome the objections of the nature above indicated and provide improvements whereby the feed roll will give way as a whole to an obstruction entering the nip, in any position longitudinally of the roll, and further, whereby the resistance to displacement of the feed roll is a predetermined uniform factor.

The invention consists in supporting the feed roll in the adjustable nip position upon a relievable predetermined resistance means common to both ends of the roll (such as a single shear pin or member) to which the force, set up by an obstruction, acting either upon both or mainly upon one end bearing of the roll, is transmitted to cause its relief.

The invention also comprises, in a multi-roll refiner or like machine having nip adjustment means for the feed roll at each end thereof, providing a displaceable abutment for each adjust-

2

ment means and connecting said abutment to a common member dependent upon a single shear pin, the arrangement being such that any displacement of the feed roll due to the entry of an obstruction in the nip, causes the pin to shear.

In the accompanying drawings which illustrate only those parts of a refiner necessary:

Figure 1 is an end view partly in section of the feed roll and the abutment means.

Figure 2 is a view on the line 2—2 of Figure 1, the roll being removed.

Figure 3 is a view showing the coupling of the abutment and the single shear pin.

Figure 4 is a partial plan of Figure 3.

In carrying the invention into effect according to one mode as described by way of example, the feed roll 1 for supplying material to the first of the refiner rolls 2 is mounted in bearings which are carried in lever members 3 pivoted in the frame 4 of the machine such that the displacement of said levers 3 by hand wheel gear may be utilised for adjusting the dimensions of the nip between the feed roll 1 and the first refiner roll 2.

The lever mounting 3 and hand wheel gear is of known kind and as each is the same for both ends of the roll, it will be sufficient to describe one only. The pivot 5 of the lever 3 is located below the roll 1 and the outer end of the lever has a stirrup 6 in which is mounted the hand wheel adjustment means for causing the displacement of the roll 1 about the pivot 5 towards or away from the first refiner roll 2. This hand wheel adjustment means comprises a hand wheel spindle 7 on which a worm is formed and this worm engages a worm wheel.

The worm wheel is internally screw threaded and acts as a bushing for a correspondingly screw-threaded thrust rod 8 which, in the case of the known arrangement, operates against a fixed abutment table or face upon rotation of the hand wheel to effect adjustment of the feed roll. According to the present improvement, however, instead of this thrust rod 8 bearing upon a fixed abutment its end is supported upon a displaceable abutment constituted by one arm 9 of the bell crank lever pivoted on a short shaft 10 which lies substantially parallel with the hand wheel worm axis.

Referring now to both bell crank levers, the arms thereof 11 which do not contact with the thrust rods are connected to a bar or member 12 common to both levers. This common bar extends transversely across the machine parallel with the axis of the feed roll. One bell crank

lever 9, 11 is pivotally connected to one end of said bar 12 and the other lever 9, 11 is pivotally connected towards the other end of the bar. In one direction the bar is extended to the adjacent side frame of the machine or some convenient feature, whereat a single shear pin 13 is located to anchor the end of the bar. The shear pin 13 engages the bar through an orifice 14 provided in the end of the bar or in an extension 15 pivotally secured thereto.

In the region of this shear pin orifice 14 the side frame 16 is provided with a seating for a ring or cage 17 in which the removable shear pin 13 is located in such a position that it may traverse the said orifice 14 on the common bar or its extension. The shear pin location may be externally covered by a suitable cap 18 secured in any convenient manner to the side frames of the machine. In one convenient form the common bar member 12 may comprise a pair of parallel rods 12a, 12b of elongated rectangular cross-section bolted together in spaced relation and having at the end towards the shear pin location a connecting rod or extension 15 pivoted at 22 between the ends of said rods 12a, 12b.

In operation, when either hand wheel spindle 7 is turned, the associated worm bushing is rotated and causes the thrust rod 8 to react against the abutment arm 9 of the bell crank levers 9, 11 anchored through the common bar 12 on the shear pin 13, and displace the corresponding end of the feed roll 1 towards the first refiner roll 2. By manipulation of both hand wheel spindles 7 the parallelism of the nip may be adjusted to the desired clearance. Through the connection of the bell crank levers 9, 11 to the common member or rod 12 the position of the abutment arms 9 is maintained entirely by the single shear pin 13, and should the shear pin fracture then both the abutments 9 will drop and consequently the feed roll nip will be relieved at both ends equally. Thus when an obstruction enters the nip tending to cause the nip clearance to increase, the pressure caused thereby will be transmitted to one or both of said abutments 9 and from thence to the shear pin 13 causing its fracture, with the result that the feed roll will retract from the refiner roll 2 and relieve the nip so that the obstruction can pass. As each end of the feed roll 1 is dependent for its position upon the shear pin 13 it will be appreciated that wherever an obstruction enters a nip anywhere along the length thereof one or other of the ends of the feed roll 1 will be displaced and the shear pin 13 will be ruptured, thereby removing the operative support from both ends of the feed roll.

At the end of the bar 12 remote from the shear pin location or at any other suitable position an adjustable cam 20 may be mounted adapted to engage the roll 23 on the arm 24 of a limit switch 21 mounted on the frame 4. The switch is included in the circuit of the driving motor for the refiner rolls so that in the event of the pin 13 being broken the motor will cut out.

I claim:

1. In a multi-roll refining machine the combination comprising: a frame; a refiner roll and means rotatably supporting said roll in fixed relationship to said frame; a feed roll; bearings rotatably supporting each end of said feed roll; means supporting said bearings for pivotal mounting thereof onto the frame about a mount-

ing axis spaced from and parallel to the axis of said roll; an abutment pivotally affixed to said frame, means including a frangible member holding said abutment against pivotal movement with respect to said frame; means carried by the housing of one of said bearings and bearing against said abutment for moving said feed roll about said mounting axis and adjusting its spacing thereof with respect to said refining roll.

2. In a multi-roll refining machine the combination comprising: a frame; a refiner roll and means rotatably supporting said roll in fixed relationship to said frame; a feed roll; bearings rotatably supporting each end of said feed roll; means supporting said bearings for pivotal mounting thereof onto the frame about a mounting axis spaced from and parallel to the axis of said roll; an abutment adjacent each end of said roll and each of said abutments being pivotally mounted onto said frame; means connecting said abutments to effect simultaneous movement of each thereof; means including a frangible member holding said connecting means for the prevention of movement of said abutments; means supported upon the housing of each of said bearings and bearing against said abutments for moving said feed roll about said mounting axis toward said refining roll; whereby upon fracture of said frangible member, said abutments will fall simultaneously and said last named means will be rendered ineffective.

3. In a multi-roll refining machine, the combination comprising: a frame; a refiner roll and means rotatably supporting said roll in fixed relationship to said frame; a feed roll; bearings rotatably supporting each end of said feed roll; means supporting said bearings for pivotal mounting thereof onto the frame about an axis spaced from and parallel to the axis of said roll; an abutment adjacent each end of said roll and each of said abutments being pivotally mounted onto said frame; a rod connecting said abutments to effect simultaneous movement of each thereof; means including a shear pin extending between said rod and said frame for preventing movement of said abutments; means supported upon each bearing housing and bearing against said abutments for moving said feed roll about said mounting axis toward said refining roll; whereby upon fracture of said shear pin, said abutments will fall simultaneously and said last named means will be rendered ineffective.
